UNITED STATES PATENT OFFICE.

GEORGE W. HAINES, OF ADIN, CALIFORNIA.

WINDMILL.

SPECIFICATION forming part of Letters Patent No. 399,887, dated March 19, 1889.

Application filed August 19, 1887. Serial No. 247,367. (No model.)

To all whom it may concern:

Be it known that I, GEORGE W. HAINES, of Adin, in the county of Modoc and State of California, have invented a new and Improved 5 Windmill, of which the following is a full, clear, and exact description.

My invention relates to an improvement in windmills, and has for its object to provide a means for regulating the same, whereby the 10 wheel will be kept turning at a regular speed in all winds, high or low, and wherein the turn-table will be constantly and automatically lubricated.

The invention consists in the construction 15 and combination of the several parts, as will be hereinafter fully set forth, and pointed out in the claim.

Reference is to be had to the accompanying drawings, forming a part of this specification, 20 in which similar letters of reference indicate corresponding parts in all the figures.

Figure 1 is a side elevation of a windmill having my improvement attached, and Fig. 2 is a vertical section on line 2 2 of Fig. 1. Fig. 25 3 is a plan view of the machine.

In carrying out the invention, A represents the turn-table, upon which a metallic cup, a, is secured, adapted to be filled with oil, and B is the turn-post, provided at its lower end 30 with a flanged ferrule, b, adapted to rest in the oil-cup a, whereby the bearing of said turn-post is constantly lubricated and said post readily turned therein. The pump-rod C, which extends upward through the turn table 35 and post, is reciprocated by a connection with the crank-arm C' of the wheel-shaft C², which may be effected by a pitman, C³, or in any approved manner.

At the side of the turn-post opposite to that 40 upon which the wheel-shaft is operated one end of the rudder-stem D is journaled, the other end, near the junction with the rudder D', being journaled in one cross-bar of a rectangular frame, D², attached at the upper end 45 of the turn-post, the wheel-shaft being journaled in the opposing cross-bar of the frame.

A weighted governor, E, is attached to the rudder-stem D, which governor is constructed of a light yet strong material and made of 50 two united sections—the body E' and the tail E². The body consists of two parallel bars, e, adapted normally to stand vertically at each

side of the frame D², which bars are connected at their upper ends by a series of fans, e', similarly set to the fans of the wheel and preferably arranged in a semicircle, as shown in Fig. 1.

The tail E² is preferably attached to the lower ends of the body-bars e, extending at an inclination therefrom, and consists of two 60 beams or bars, e², brought substantially together at their outer ends and united to an intermediate short bar, e³, carrying a weight, F.

The governor is bolted to the rudder-stem by bars F', attached to the body-bars e, and 65 also secured to the said stem—one bar above the frame D² and the other below. The weight F is so adjusted upon the tail and is made heavy enough to just balance the governor in its normal or upright position when the wheel 70 is running at a predetermined speed, and the rudder is also held by said weight in a position to keep the wheel squarely facing the wind. As the wind increases in force, the pressure against the governor-fans operates 75 upon the same, as on the wheel, causing the body of the governor to turn downward, thereby lifting the weighted tail, which action also turns the rudder from a perpendicular to an angle with the wind or to a horizontal 80 or edgewise position in relation to the same, which movement compels the wheel to turn partly out of the wind. When the governor operates to throw the wheel out of the wind, the weight and rudder operate to hold 85 the wheel to an extent and prevent it from going too far out. Thus the wheel is kept as near as possible to an even and regular speed in all winds, whether high or low.

Below the turn-table, upon the pump-rod, a 90 swivel, G, is held to slide, provided with two opposing apertures, g, as shown in Fig. 2, through which apertures chains H and H' are passed up through the turn-post and out near the top on opposite sides, the upper end 95 of the chain H being attached to the body of the governor near the fans upon one side, as at h, the upper end of the other chain, H', being attached to the tail near the body, at the edge opposite the edge to which said chain H is fastened and on the same side, as illustrated at h'. The chain H has a button, h², outside its aperture to limit its play, and the said chain is utilized when it is desired to stop the 100

mill, which is accomplished by pulling down upon the swivel, which by reason of the said button draws upon chain H, while chain H' passes freely through. This action turns 5 down the governor to a horizontal position, as shown in dotted lines, Fig. 2, thereby changing the position of the rudder also and throwing the wheel out of the wind. When it is required to start the mill, the chain H is loosened and the weight brings the regulator to 10 its normal position.

The chain H' is attached to the swivel when the wheel is running, so that in the event of a high wind it helps to hold the wheel steady. 15 When one chain is attached, the other is detached.

Having thus described my invention, what I claim as new, and desire to secure by Letters Patent, is—

In a windmill, the combination, with the 20 turn-post B, the pump-rod C, the rudder-shaft D, and the governor E, secured to the rudder-shaft and provided with the arms h, of the swivel G, provided with the apertures g and mounted on the pump-rod, and the ropes or 25 chains H H', secured to the arms h of the governor and passing down through the turn-post and out through the apertures of the swivel, the chain H being provided with the button h², substantially as herein shown and 30 described.

GEORGE W. HAINES.
